HAIR WAVING DEVICE

Filed Feb. 18, 1928

Fig: 1

UNITED STATES PATENT OFFICE

HANNAH M. HART, OF CHICAGO, ILLINOIS

HAIR-WAVING DEVICE

Application filed February 18, 1928. Serial No. 255,328.

The present invention relates, generally speaking, to hair wavers, and is more particularly concerned with a curling fork for use in a so-called permanent wave machine, 5 for imparting to the hair the "Marcel" wave in a simple and efficient manner.

The permanent wave machine, as is well known, comprises a plurality of tubular heating elements, and serves for producing simple coiled curls, by means of a tapered round curler rod. A strand of hair is coiled around this rod and fastened to it by means of a string. A moist pad is then wrapped around the strand of hair coiled on the rod, and, 15 thus prepared, the rod is inserted into a heating element on the machine. When current is applied, the strand of hair is steamed and baked in place, producing a simple coil or curl, which is termed a permanent wave.

20 A so-called "Marcel" wave, which is a more natural wave than the simple curl wave, cannot be produced in a permanent wave machine by the ordinary means. It is applied manually by an operator manipulating a curling iron of special construction.

It is the object of the present invention to produce a "Marcel" wave in an ordinary permanent wave machine of known construction, in substantially the same successive steps at 25 present necessary for producing a simple coiled wave.

In order to accomplish the above, and other objects and features which will be apparent as the description progresses, I have invented 35 a curling fork which may be used in place of the ordinary curling rod, if it is desired to produce a permanent Marcel wave.

The invention will be better understood and 40 appreciated from a detailed description with reference to the accompanying single sheet of drawings which forms a part of this specification.

Referring now to the drawings,

45 Fig. 1 shows the curler fork;

Fig. 2 is a cross section taken on line A—A of Fig. 1;

50 Fig. 3 illustrates a locking hub which serves to lock the prongs of the fork and to tension a strand of hair placed on the prongs;

Fig. 4 is a side view of the hub shown in Fig. 3;

Fig. 5 shows a modified and preferred form of locking hub;

Fig. 6 illustrates a strand of hair arranged 55 on the prongs of the curler fork, tensioned and locked in place;

Figs. 7 and 8 are side and top views, respectively, of an adjusting bracket whose use will be explained presently; and 60

Figs. 9 and 10 illustrate a preferred form of the bracket shown in Figs. 7 and 8.

Fig. 11 is a view showing in detail and on an enlarged scale the free end portions of the 65 prongs of the device.

All parts are numbered alike in the various figures. Therefore, a certain figure will only be referred to if necessary for explaining specific details.

Having explained, in a general manner, 70 the invention and the various figures shown in the drawings, the detailed description will now be proceeded with.

Figure 1 illustrates a curler fork as contemplated by the invention, having prongs 3 and 4 tapering toward the base, which terminates in a forked hub, forming a slit 2 for attaching a strand of hair to the fork as shown in Fig. 6. It will be seen from the cross section Fig. 2, that the prongs 3 and 4 of the curler fork are oval-shaped, and it may be said at this point, that the prongs as well as other parts of the curler fork are smooth and finished to prevent rough spots or protruding parts from catching and thus injuring the hair. At the lower end, the prongs 3 and 4 terminate in guide and lock parts 5 and 6, which are parallel to the slot 2 at the base of the fork, and thus deviate 80 slightly from the general direction of the prongs 3 and 4.

Figs. 3 and 4 illustrate side and top views 85 of a locking hub 7, provided with holes 8 and 9 for sliding on the lock members 5 and 6 of the fork. An angular lever 10 having an arm 12 is rotatably mounted in the hub 7, on a pin 11.

When a strand of hair is arranged on the 90 curler fork as shown in Fig. 6, the locking hub 7 is pushed on the ends 5 and 6 of the 100

prongs 3 and 4, with the lever 10 withdrawn. When this lever 10 is pushed in place, it will be obvious that its arm 12 will engage the end of one prong, thereby locking the two 5 prongs in place.

It will be understood that the winding of the strand of hair on the fork will produce a tendency to draw the two straight prongs 3 and 4 together. Now, by attaching the locking hub 7, this tendency will be counteracted, 10 and the two prongs of the fork will be drawn apart to an extent determined by the corresponding openings in the hub. This drawing apart of the prongs upon locking the same 15 will put a slight tension on the strand of hair, attaching it firmly to the prongs of the fork.

In Fig. 5, I have shown a modified form of a hub which locks automatically. This hub consists of a body 13 provided with openings 20 14 and 15 for engaging the ends 5 and 6 of the prongs. These openings are provided with grooves 16 and 17, and resting in these grooves are semi-circular springs 18 and 19, tensioned to grip the ends 5 and 6 of the 25 prongs when inserted into the openings 14 and 15.

In Fig. 6 is illustrated a curler fork as shown in Fig. 1, a strand of hair wound thereon, and locked in place by means of a hub as 30 shown in Fig. 5.

The assembly as shown in Fig. 6, is wrapped in the usual moist pad, and then inserted into a tubular heating element on the permanent wave machine. When current is 35 applied, the strand of hair will be steamed and baked in place, and the wave produced will be a "Marcel" wave of natural texture and form.

It may occur, in some instances, that the 40 hair to which a Marcel wave is to be applied, is short, and that a strand arranged on the fork as indicated in Fig. 6, does not cover the entire length of the prongs. In this case, the operator will make use of the adjustable 45 bracket shown in Figs. 7 and 8, or of the one shown in Figs. 9 and 10.

The bracket shown in Figs. 7 and 8 consists of a body member 21 holding two plungers 22 and 23, which are slidably mounted in the 50 body member 21 by means of a spring 24. Each plunger has a groove for engaging one of the prongs of the fork. The bracket is inserted at the lower, open end of the prongs, and pushed upward to adjust the successive 55 curls in each series closely to each other. The hub is then attached as usual to the ends of the prongs to lock the assembly together.

The adjusting bracket illustrated in Figs. 60 9 and 10 consists of two mounting plates 27 and 28 held together by a pin 35. Rotatably mounted on this pin, and located inside these plates are two spring members having spring 65 branches 29, 30, and 31, 32, respectively. These springs act upon U-shaped members 33

and 34 which are slidably mounted inside the plates 27 and 28.

It will be obvious without elaborate explanations that the adjusting bracket as shown in Figs. 9 and 10 is self-aligning in a simple and efficient manner, and may be pushed up and down the fork prongs to adjust the curls. The plates 33 and 34 will slide inside the prongs and will tend to keep the prongs apart. The friction created thereby 75 will be sufficient to hold the bracket in place.

There is no difference in the successive steps of producing a "Marcel" wave as explained in the foregoing paragraphs, when compared with the process of producing an ordinary coiled wave. The difference resides merely in arranging the strand of hair on the prongs or extensions, as shown in Fig. 6, instead of simply winding it in successive turns on a round rod, as is done at present for making a permanent (curl) wave. The product will, accordingly, be different, that is, it will be a permanent ("Marcel") wave.

The material for making the fork and the hub may be an aluminum alloy or any suitable resilient and durable matter, and the fork may be cast or punched and then finished by any well-known and desirable process.

It will be apparent that modifications may suggest themselves readily to anyone experienced in the art. I, therefore, desire it to be understood that I do not want to be limited in the application of the invention to the precise structure shown and explained, but only to the claims which follow.

What is claimed is:

1. A device for use with a permanent wave machine and adapted to produce a Marcel wave, comprising a fork having two prongs tapering toward the base, a forked member integral with said base and having two prongs projecting in parallel therefrom in a direction opposite to said tapering prongs, said tapering prongs terminating in guide members disposed parallel to each other, a locking member having openings to receive said guide members, and means in said locking member to lock said tapering prongs thereto.

2. A device of the class described, comprising a base, a fastening member projecting from said base, a plurality of resilient prongs projecting from said base oppositely to said member, a locking member provided on one side with openings to receive said prongs, and means in said locking member to lock said prongs in place.

3. A hair waver of the class described comprising a hair supporting fork, a socket associated therewith, means on said socket for fastening a strand of hair thereto, a terminal member, a plurality of openings in said member for receiving said prongs in definitely spaced relation, and locking means in said

member for securing said prongs to said member.

4. A hair waver of the class described comprising a hair supporting fork having a plurality of prongs, means on the base of said fork for fastening a strand of hair thereto, a terminal member, means in said member for definitely spacing said prongs and for tensioning a strand of hair supported thereon, and means in said member for locking said prongs.

5. A hair waver of the class described comprising a hair supporting fork having a plurality of resilient prongs, means on the base of said fork for fastening a strand of hair thereto, a separate terminal member for closing and for bridging the ends of said prongs, means in said member for automatically spacing said prongs definitely and for tensioning thereby a strand of hair supported thereon when said member is attached to said prongs, and means in said member for automatically locking said prongs thereto.

6. A hair waver comprising a member for fastening a strand of hair thereto, a plurality of resilient extensions for arranging said strand of hair thereon in a corresponding plurality of oppositely disposed successive curls, each extension serving as an axis for a series of curls, a terminal member, means in said member for automatically spacing said extensions definitely and for thereby automatically tensioning said strand of hair supported thereon, and means in said member for automatically locking said extensions.

7. A hair waver comprising a member for fastening a strand of hair thereto, a plurality of extensions for arranging said strand of hair thereon in oppositely disposed series of successive curls, each extension serving as an axis for a series of curls, a terminal member, means in said member for automatically spacing said extensions and for tensioning thereby said strand of hair arranged thereon, and means in said member for automatically locking said extensions in place.

8. A hair waver comprising a plurality of straight and smoothly finished stationary extensions projecting from a common base and integral therewith for arranging a strand of hair thereon in a series of curls, each extension serving as an axis for a series of curls, a terminal member for bridging and for covering the ends of said extensions, means in said member tending to separate said extensions for tensioning said strand of hair arranged thereon, and means in said member for locking said extensions.

9. A hair waver comprising a plurality of straight and smoothly finished stationary extensions for arranging a strand of hair thereof in oppositely located series of curls, each extension serving as an axis for a series of curls, a bracket for slidably engaging said extensions to arrange said series of curls close-

ly to each other, a separate terminal member, means in said member for spacing said extensions and for thereby tensioning said strand of hair arranged thereon, and means in said member for locking said extensions relative to said terminal member and to each other.

10. A hair waver comprising a plurality of straight and smoothly finished extensions projecting from a common base and integral therewith for arranging a strand of hair thereon in a series of curls, each extension serving as an axis for a series of curls, a bracket having means for slidably and adjustably engaging said extensions to arrange the curls in each series closely to each other, a separate terminal member for bridging and for closing the ends of said extensions, means in said member tending to separate said extensions for tensioning said strand of hair thereon, and means in said member for locking said extensions.

11. A hair waver comprising prongs adapted to receive a strand of hair wound thereon in alternately opposite directions, said prongs being movable toward and away from each other, and means for forcing the prongs apart to tension the hair wound thereon and for thereafter releasably securing them against movement toward each other.

12. A hair waver comprising a fork having two resilient prongs secured together at one end and free at the other end, and releasable means for forcing the free ends of the prongs apart to tension hair wound thereon and for thereafter holding the prongs against movement toward each other.

13. A hair waver comprising prongs adapted to receive a strand of hair wound thereon in alternately opposite directions, said prongs converging toward one end thereof, and a member adapted to be slid along the prongs for compacting the coils of hair wound thereon, said member acting to spread the prongs apart thereby tensioning the coils of hair.

In witness whereof I hereunto subscribe my name this 14th day of February, A. D. 1928.
